CLAIM

I claim the ornamental design for an industrial food dispenser for animals, as shown and described.

DESCRIPTION

FIG. 1 is a top, right perspective view of an industrial food dispenser for animals;

FIG. 2 is a front elevation view thereof;

FIG. 3 is a rear elevation view thereof;

FIG. 4 is a top plan view thereof;

FIG. 5 is a bottom view thereof;

FIG. 6 is a right side elevation view thereof; and,

FIG. 7 is a left side elevation view thereof.

1 Claim, 7 Drawing Sheets
